DESIGN.

—o—
T. VILLAGE.

DOOR KNOB OR BELL PULL.

No. 17,207.

Patented Mar. 22, 1887.

UNITED STATES PATENT OFFICE.

THOMAS VILLAGE, OF SOUTH NORWALK, CONNECTICUT, ASSIGNOR TO THE
LOCKWOOD MANUFACTURING COMPANY, OF SAME PLACE.

DESIGN FOR A DOOR-KNOB OR BELL-PULL.

SPECIFICATION forming part of Design No. 17,207, dated March 22, 1887.

Application filed February 16, 1887. Serial No. 227,851. Term of patent 7 years.

To all whom it may concern:

Be it known that I, THOMAS VILLAGE, a citizen of the United States, residing at South Norwalk, in the county of Fairfield and State of Connecticut, have invented and produced a new and original Design for Door-Knobs or Bell-Pulls; and I do declare the following to be a full, clear, and exact description of the same, reference being had to the accompanying photographic illustration, forming a part thereof, which represents my improved design in front elevation.

My new design has relation to the class of knobs used in builders' hardware—for example, door-knobs, bell-pulls, &c.; and it consists in the special configuration of the knob, substantially as hereinafter described, and then pointed out in the claims.

The face of the knob is rounded in the usual manner, it being, if preferred, slightly flattened at the top.

1 denotes a circular bead surrounding a panel at the center of the face of the knob, and 2 a circular bead at the edge of the knob—25 that is, at its greatest diameter.

3 denotes a series of cones, the bases of which rest against bead 2 and the points of which extend nearly up to bead 1. The groundwork within the panel at the center of the knob consists of diamond-shaped figures 4, each of which has within it a cross-shaped figure, 5, the four arms being of equal length and each of them rounded.

7 denotes a raised vase resting upon an ornamental support consisting of bars 8, having between them X-shaped figures 9, the arms of which are made angular. 10 denotes pendants beneath the lower bar. The vase is filled with raised conventional representations of flowers (denoted by 11) and leaves, (denoted by 12,) one of the leaves at the left being represented as broken from its stem.

Having thus described my invention, I claim—

1. In a design for a door-knob, as herein described and shown, a circular panel surrounded by a raised bead and having within it a representation of a vase containing flowers and leaves, substantially as shown. 45

2. In a design for a door-knob, as herein described and shown, a circular panel surrounded by a raised bead, and a vase containing flowers and leaves and resting upon an ornamental support. 50

3. In a design for a door-knob, as herein described and shown, a circular panel surrounded by a circular bead having a groundwork consisting of diamond-shaped figures, each of which has within it a cross-shaped figure with rounded arms, and a raised vase upon said panel, containing leaves and flowers and resting upon an ornamental support, substantially as described. 55

4. In a design for a door-knob, as herein described and shown, beads 1 and 2, cone-shaped figures 3, resting upon bead 2, a panel within bead 1, having a vase containing flowers and leaves, and an ornamental support for said vase. 60

5. In a design for a door-knob, as herein described and shown, a circular panel having a raised vase containing leaves and flowers, a support therefor consisting of bars 8, having X-shaped figures with angular arms between them, and pendants 10 beneath the lower bar. 70

6. In a design for a door-knob, as herein described and shown, a circular panel having an ornamental groundwork, a vase and ornamental support therefor, and flowers and leaves, one of said leaves being broken from its stem. 75

In testimony whereof I affix my signature in presence of two witnesses.

THOMAS VILLAGE.
